CLAIM

The ornamental design for a wearable electric field detector as shown and described.

DESCRIPTION

FIG. 1 is a top perspective view of a wearable electric field detector shown from the rear;

FIG. 2 is a bottom perspective view of the wearable electric field detector shown from the front;

FIG. 3 is a bottom plan view of the wearable electric field detector;

FIG. 4 is a top plan view of the wearable electric field detector;

FIG. 5 is a rear elevation view of the wearable electric field detector;

FIG. 6 is a front elevation view of the wearable electric field detector;

FIG. 7 is a right side elevation view of the wearable electric field detector; and,

FIG. 8 is a left side elevation view of the wearable electric field detector.

The elements shown in broken line in the drawings is for the purpose of showing environmental structure and forms no part of the claimed design.
